Primary Examiner — Marianne Pandozzi(74) *Attorney, Agent, or Firm* — Thomas C. Feix; Stacy H. Combs(57) **CLAIM**

The ornamental design for a water pitcher lid or portion thereof with an attached flume, as shown and described.

DESCRIPTION

FIG. 1 is an exploded perspective view of a water pitcher lid or portion thereof with an attached flume showing our new design;

FIG. 2 is a front perspective view of the lid or portion thereof;

FIG. 3 is a top plan view of FIG. 2;

FIG. 4 is bottom plan view of FIG. 2;

FIG. 5 is a left side elevational view of FIG. 2;

FIG. 6 is a right side elevational view of FIG. 2;

FIG. 7 is back view of FIG. 2; and,

FIG. 8 is a front view of FIG. 2.

The broken lines in the drawing depict environmental subject matter only and form no part of the claimed design.

1 Claim, 3 Drawing Sheets(56)
